(Cl. D89—1)

To all whom it may concern:

Be it known that we, Henry J. Talge and Elton F. Whitfill, citizens of the United States, both residing at Kansas City, in the county of Jackson and State of Missouri, have invented a new, original, and ornamental Design for a Fruit Juicer, of which the following is a specification, reference being had to the accompanying drawing, forming part thereof, in which

Fig. 1 is a front perspective view of a fruit juicer embodying our new design.

Fig. 2 is a rear perspective view of the fruit juicer and

Fig. 3 is a front perspective view of the fruit juicer showing the same in open position.

We claim:

The ornamental design for a fruit juicer, substantially as shown.

HENRY J. TALGE,
ELTON F. WHITFILL.
